(57) **CLAIM**

The ornamental design for lens carrier, as shown and described.

DESCRIPTION

FIG. 1 is a front elevational view of a lens carrier for our new design;

FIG. 2 is a rear elevational view thereof; and,

FIG. 3 is a side elevational view, wherein the other side is a mirror image thereof.

The broken lines showing certain portions of the lens carrier are for the purpose of illustrating environment structure and form no part of the claimed design.
